UNITED STATES PATENT OFFICE.

PHILIP DOUGLAS PARSONS, OF PHILADELPHIA, PENNSYLVANIA.

TENSION MEANS FOR LAWN-TENNIS RACKETS.

1,140,282.

Specification of Letters Patent. Patented May 18, 1915.

Application filed May 2, 1914. Serial No. 836,005.

To all whom it may concern:

Be it known that I, PHILIP D. PARSONS, a citizen of the United States, residing at Philadelphia, in the county of Philadelphia and State of Pennsylvania, have invented 5 certain new and useful Improvements in Tension Means for Lawn-Tennis Rackets; and I do hereby declare the following to be a full, clear, and exact description of the 10 invention, such as will enable others skilled in the art to which it appertains to make and use the same, reference being had to the accompanying drawings, and to the letters and figures of reference marked thereon, which 15 form a part of this specification.

This invention relates to new and useful improvements in devices for regulating the tension of the strings upon tennis rackets and consists of a simple and efficient device 20 of this nature providing means whereby strings may be drawn taut without the necessity of restringing the whole racket.

My invention comprises various details of construction, combinations and arrangements of parts which will be hereinafter 25 fully described, shown in the accompanying drawings and then specifically defined in the appended claim.

I illustrate my invention in the accompanying drawings, in which:

Figure 1 is a side elevation of a racket, a part being shown in section. Fig. 2 is an enlarged detail view of the nut and threaded screw eye.

Reference now being had to the details of the drawings by letter, A designates the frame of a racket and B the strings. Holes E are formed in the racket frame, one hole having a shoulder adapted to receive and hold the knotted end of the string, said string being adapted to engage an eye D formed in the screw D' which fits a hole F in the opposite side of the frame. A nut, designated by letter K, is mounted upon said 45 threaded screw and is adapted to turn in an

enlarged part of the hole in which the threaded end of the screw projects. Slots N are formed in the outer end of the nut, forming a convenient means for engagement with a key R, having lugs projecting from 50 the end thereof and which are designed to engage said slots and forming a convenient means whereby the nut may be turned in one direction or the other accordingly as it may be desired to impart a longitudinal movement to the screw to regulate the tension of the string.

By the provision of a tightening means embodying the features of my invention, it will be noted that a simple and efficient 60 means is afforded whereby the individual strings of the racket may be conveniently tightened without necessity of restringing the whole racket.

What I claim to be new is:

In combination with the frame of a racket having cylindrical apertures therein enlarged at the outer ends, a screw provided with a rounded unthreaded end which is apertured, a strand passing through one 70 aperture and having a knot engaging a shoulder therein and passing through the aperture in said screw, the unthreaded end of the screw being adapted to engage and hold the strand frictionally at points diametrically opposite against the marginal edge of the aperture in which the screw is located, a washer engaging a shoulder in the aperture in which the screw is mounted, and a hollow nut, internally threaded, engaging 80 the screw and bearing against said washer, the outer end of the nut having notches therein for the reception of a key.

In testimony whereof I hereunto affix my signature in presence of two witnesses.

PHILIP DOUGLAS PARSONS.
